MARIAN ROMANOWICZ AND JOHANN ROMANOWICZ, OF VIENNA, AUSTRIA.

PHOTOGRAPHIC FILM OR PLATE PACK.

Application filed June 2, 1926, Serial No. 113,195, and in Austria August 4, 1925.

Our invention relates to photographic plates either rigid or flexible of glass, celluloid or other suitable material provided with a pulling strip and a protecting sheet. Such plates are usually packed in the form of piles in boxes of opaque material provided with an exposition opening and a slot through which the pulling strips extend to the outside in such a manner that by pulling 10 the pulling strip of the uppermost plate of the pile, this uppermost plate is first pulled backwards over the next following plate, then sinks down to the bottom of the pile of not yet exposed plates and finally 15 slides forwards below the lowermost plate of such latter pile so that it is covered thereby while the said next following plate becomes the uppermost plate of the pile and is brought into position ready for exposition. 20 The arrangement of the pulling strip and of the protective sheet heretofore used is open to the objection that while a plate is being pulled backwards and forwards again this plate or the neighbouring plates are 25 liable to be injured by the pulling strip or by one plate sliding over the other. Moreover, the plates slipping below the pile are liable to get into an oblique position.

The object of our invention is to meet 30 these objections and to provide a plate so constructed that it can be reliably exchanged without any risk of damage to it or the neighbouring plates.

With this object in view our invention 35 consists in that each plate has attached to one and the same edge of it a protecting sheet of substantially the same length as the plate and a pulling strip of at least double the length of the plate, the pulling strip 40 being interposed between the protecting sheet and the plate.

When arranged in a pile the edges of the plates to which the pulling strips and the protecting sheets are attached, hereinafter 45 referred to as the front edges, are all on the same side, the front sides of the pile, and that the pulling strip of this top plate of the pile extends along the back of this top plate, that is to say along the side of 50 the plate adjacent to the next following or second plate of the pile, then down the back side of the pile and thence to the front side of the pile again and outwards through the usual slot passing below the pulling strip 55 of the said second plate of the pile and so on as is customary in plate piles of this

class. The protecting sheet of the top plate of the pile is thus according to our invention located between the pulling strip of the top plate and the top face of the second plate 60 and so on. Below the lowermost plate of the pile there is provided a spring supported bottom plate of about the same size as the photographic plate permanently forcing upwards the pile above it which the pulling 65 strip of the lowermost photographic plate passes on being pulled outwards. If desired we may interpose between the bottom face of the plate and the pulling strip a backing sheet of substantially double the length of 70 the plate and attached to the same edge of the plate as the pulling strip and the protecting sheet. In the pile the backing sheet of each plate follows the pulling strip of the same plate, but need not project outwards 75 through the slot through which the pulling strip extends to the outside.

In the annexed drawings we have shown 80 by way of example two embodiments of our invention.

Fig. 1 is a sectional side elevation of a 85 photographic plate provided with a protecting sheet and a pulling strip.

Fig. 2 is an inverted plan view of the same.

Figs. 3, 4, 5 and 6 show in sectional side elevation a pile of plates as shown in Figs. 1 and 2 arranged in a box and illustrating on a somewhat exaggerated scale various positions of the top plate, the pulling strip 90 and the protecting sheet while pulling such plate from the uppermost below the bottom plate.

Figs. 7 and 8 are views similar to Figs. 1 and 2 showing a plate provided with a 95 backing sheet, a pulling strip and a protecting sheet.

Figs. 9, 10, 11 and 12 are views corresponding to Figs. 3 to 6 illustrating the various positions of the plate shown in Figs. 100 7 and 8 while being pulled from the uppermost position below the bottom plate.

In Figs. 1 and 2, 1 is the photographic plate either rigid or flexible of any known or desired type. To one edge 2 of this plate 105 are attached preferably by cementing a protecting sheet 3 of substantially the same width and length as the plate and a pulling strip 4 of more than double the length of the plate, the pulling strip 4 being arranged 110 between the bottom face or back of the plate 1 and the protecting sheet.

The protecting sheet 3 is flexible and somewhat elastic and made of some suitable material of the required strength and preferably impervious to light, such as black paper. 5 The pulling strip 4 is likewise made of some suitable flexible material preferably impervious to light having the required strength, such as black paper.

Fig. 3 shows a pile of any desired number 10 of plates, 1, 11, 21 arranged in the form of a pile say three, in a rectangular box 30 of about the same width and slightly more than double the length of the plates. The protecting sheet 3 of the uppermost plate 1 of the pile is in direct contact with the top face 15 of the next following plate 11. The pulling strip 4 of the plate 1 extends from its front edge 2 to its rear edge, then passes down along the rear side of the pile and finally 20 extends forwards below the pulling strip 14 of the second plate 11 from top and out through the slot 31 of the box 30. Similarly the protecting sheet 13 of the second plate from top is in direct contact with the 25 third plate 21 while its pulling strip 14 passes down the rear side of the pile and forwards to the slot 31 between the pulling strip 4 of the top plate 1 and the pulling strip 24 of the third plate from top of the pile and 30 so on.

The lowermost plate 21 of the pile need 35 not be provided with a protecting sheet nor with a pulling strip since usually the lowermost plate is not exchanged. The supporting plate 22 of the pile, made of card board or other suitable material permanently forces upwards the plates above it against the top wall of the box 30 by springs 32. Its rear edge serves also for folding round it the 40 pulling strip of the lowermost plate of the pile if such strip be provided. The rear edges of the protecting strips 3, 13, 23 preferably slightly project beyond the rear edges of their respective plates and are sharply 45 bent downward at such rear edges for a purpose described later on.

By pulling the pulling strip 4 of the uppermost plate 1 of the pile through the slot 31, see Fig. 4, the plate 1 is first moved 50 backwards, but its pulling strip 4 is held out of contact with the top face of the second plate 11 by the protecting sheet 3 so that neither the plate 1 nor its pulling strip 4 do not slide along in contact with and rub 55 against the top face of the second plate 11 and injure it. Nor does the protecting sheet 3 slide along and rub against the top face of the second plate 11 because this sheet slightly adheres to the top face of the second plate 11 and therefore as the front edge 2 of the plate 1 and the protecting sheet 3 are pulled 60 backwards the front part of the sheet 3 is folded down on its rear part at 5 and it is not the protecting sheet 3 bodily, but only 65 the bight 5 that moves along the top face of

the second plate 11 while the body of the protecting sheet is simply raised or rolled off the plate 11 without sliding along or rubbing against the latter, as is clearly seen in Fig. 4.

When the plate 1 has reached its extreme 70 rearward position shown in Fig. 5 and its front edge 2 has come clear of the rear side of the pile, the projecting sheet 33 of this plate is turned up against this rear side of the pile and the rear bights of the pulling 75 strips 14, 24 of the plates 11, 21. As the pulling of the strip 4 is continued the front edge 2 of the plate 1 slips below the pulling strip 14 of the next plate 11 of the staple the protecting sheet 3 of the plate 1 being folded 80 or rolled down on the top side of plate 1 without rubbing against the same and thus protecting this top side of the plate 4 against injuring by the pulling strip 14 as is clearly seen in Fig. 5. Finally the plate 1 reaches 85 the position shown in Fig. 6 in which it has fully slipped under the supporting plate 32 and the pile of plates 11, 21. The bent rear edge of the protecting sheet 3 is thus caused 90 to engage the rear end of the plate 3, Fig. 6. 95

If now the pulling strip 14 of the next plate 11 is pulled outwards the plate 11 would slip between the pulling strip 24 of the plate 21 and the protecting sheet 3 since the rear edge of this protecting sheet 3 100 engages the rear edge of the plate 1, Fig. 6. Thereby any injuring to the top face of the plate 1 is prevented.

While the arrangement above described 105 is fully satisfactory in case it is the top face of the plates which is sensitized or provided with a sensitized coating, it would be objectionable in the case of plates the bottom face of which is sensitized or provided with a sensitized coating because owing to the fact that the bottom face of the plate 11, Fig. 6 must slide along and consequently rub against the protecting sheet 3 next below it, the bottom face is liable to be injured. Therefore we prefer to use backing sheets 110 of some flexible some-what elastic material 110 impervious to light such as black paper and to permanently attach them to the front edge of the associated plates, as shown in Figs. 7 and 8. In these, 1 is the plate, 2 is the front edge, 3 its protecting sheet, 4 its pulling strip and 6 its backing sheet. The width of the backing sheet is substantially 115 the same as that of the plate and of its protecting sheet, while the length of the backing sheet having its front end permanently attached to the edge 2 of the plate is slightly less than that of the pulling strip, but preferably at least twice the length of the plate. The backing sheet 6 is located between the bottom face of the plate and its pulling strip and the backing sheet 6 and the pulling strip 4 are located between the plate 1 and the protecting sheet 3. The plates thus 120 equipped are again packed in a pile in a box 125 130

30 having a slot 31 for the free ends of the pulling strip to pass through to the outside as shown in Figs. 9 to 12 in exactly the same manner as in Figs. 3 to 6 while the free ends 5 of the backing strips 6 are prevented from moving forwards by any suitable means. Assuming the uppermost plate 1 of the pile has been brought to the bottom of the pile by pulling its pulling strip 4 into the position shown in Fig. 10 in which the backing strip of the plate 1 has been omitted then on pulling outwards the pulling strip 14 of the then uppermost plate 11 of the pile the protecting sheet 3 of the same behaves 15 exactly like the protecting sheet 3 in the arrangement described with reference to Figs. 3 to 6. The backing sheet 16 held between the bottom side of the plate and the pulling strip must, of course, follow the pulling strip forming a bight 17 below the plate 11 and in rear of the pile until the front end 2 of the plate is about to slip below the pile. As the pulling of the strip 14 is continued the plate 11 slips between the bottom 20 part of its own backing strip 16 and the bottom part 26 of the next following plate 21 of the pile as seen in Fig. 11. This bottom part of the backing strip 16 being prevented as above stated from moving forward 25 through the slot 31 it leaves unaffected the protecting sheet 3 immediately below it even if the rear edge of the protecting sheet is not bent downwards. While the front edge 2 of the plates 1 moves forwards below the front end of the backing sheet 26 the bight 17 of the backing sheet 16 will fold or roll down on the top face of its front part and therefore will not slide or rub neither on the bottom face of its plate 11, as is clearly 30 seen in Fig. 11. Thus any injury to any of the plates, protecting sheets and backing sheets is fully avoided. Finally the parts reach the position shown in Fig. 12 the protecting sheet 13 being flat on the top face 35 and the backing sheet 5 being folded on the bottom face of the plate 11. The same operation is repeated in exchanging the other plates of the pile.

The lowermost plate of the pile may or 50 may not be provided with a pulling strip and protecting sheet and backing sheet.

The use of the protecting sheets together with the backing sheets is also advantageous with plates having a sensitized top face as 55 by their combined action the plate is prevented from working sideways and readily slips into a pile even if the latter is acted upon by springs. In this case the uppermost plate of the pile which on being exchanged slides on the bottom of the box 60 need not be provided with a backing sheet.

From the above description of the arrangement it will be understood that any risk of injury to the plates during exchanging is avoided with certainty and that the

plates are also protected against undesired action of light.

What we claim is:

1. In combination with a photographic plate, a protecting sheet and a pulling strip 70 both of which are attached to the same edge of the plate, the protecting sheet being of substantially the same length and width as the plate, the pulling strip being at least twice as long as the plate and the pulling strip being located between the plate and the protecting sheet.

2. The combination of a plurality of photographic plates each of which is provided with a protecting sheet and a pulling 80 strip both of which are attached to the same edge of the plate, the protecting sheet being of substantially the same length and width as the plate, the pulling strip being at least twice as long as the plate and the pulling 85 strip being located between the plate and the protecting sheet, the plates being arranged in a pile, the pulling strips of the successive plates passing from the front edges of their associated plates to the rear 90 ends thereof, then down the said pile and then forwards again underneath the pulling strip of the next following plate from top with a box adapted to receive the said pile and having a slot in its front end, the free 95 ends of the pulling strip passing through the said slots to the outside of the box.

3. In combination with a photographic plate, a protecting sheet and a pulling strip 100 both of which are attached to the same edge of the plate, the protecting sheet being of substantially the same length and width as the plate, the pulling strip being at least twice as long as the plate and the pulling strip being located between the plate and the protecting sheet and a backing sheet 105 attached to the same edge of the plate as the said pulling strip and protecting sheet, the said backing sheet being located between the plate and the pulling strip and being 110 of substantially the same width as the plate and being of a length greater than that of the plate.

4. The combination of a plurality of photographic plates each of which is provided with a protecting sheet and a pulling 115 strip both of which are attached to the same edge of the plate, the protecting sheet being of substantially the same length and width as the plate, the pulling strip being at least twice as long as the plate and the pulling strip being located between the plate and the protecting sheet and with a backing sheet attached to the same edge of the plate 120 as the said pulling strip and protecting sheet, the said backing sheet being located between the plate and the pulling strip and being of substantially the same width as the plate and being of a length greater than 125 that at the plate, the plates being arranged 130

in a pile, the pulling strips and backing sheets of the successive plates passing from the front edges of their associated plates to the rear ends thereof, then down the said pile and then forwards again underneath the pulling strip of the next following plate from top, with a box adapted to receive the said pile and having a slot in its front end,

the free ends of the pulling strip passing through the said slots to the outside of the box and with means for preventing the said backing sheets from moving out of the box. 10

In testimony whereof we have affixed our signatures.

MARIAN ROMANOWICZ.
JOHANN ROMANOWICZ.
